UNITED STATES PATENT OFFICE.

LAWRENCE H. LEVINSON, OF CHICAGO, ILLINOIS.

SHADE HOLDER.

Application filed August 30, 1926. Serial No. 132,441.

The invention relates to shade holders and particularly to those employed for supporting shades of bridge lamps in functional position, although the invention may be generally employed where a shade is to be supported.

In mounting a shade, it has been customary to provide a holder ring which is provided with screw thread to be secured to the upper part of a lamp post or to a socket and with a plurality of wires to connect the holder ring with the upper ring of the shade. In this construction the holder ring is of comparatively thin metal and is provided with a plurality of apertures through which the ends of the wires from the shade ring are curled. The disadvantages entailed in this construction are that the cost of mounting the shade is rather high and that the assembly is not rigid, permitting a certain play of the shade under the influence of jars or shocks.

It is, therefore, an object of the invention to provide a shade holder ring adapted to be rigidly secured to the shade so as to preclude swaying of the shade under the influence of jars.

Another object aims at the provision of a holder ring which is sturdy and may be cheaply connected with the shade.

With these and other objects in view which will become apparent upon perusal of the invention, the latter comprises the means set forth in the following specification, particularly pointed out in the claims forming a part thereof, and illustrated in the accompanying drawings, in which:

Figure 1 is an elevational view of a bridge lamp;

Figure 2 is a top plan view of a shade in which the invention is incorporated;

Figure 3 is an enlarged bottom plan view of a shade ring holder;

Figure 4 is a section on the line 4-4 of Figure 3; and

Figure 5 is a sectional elevation of a well-known ring holder.

Referring to the several views in the drawing, 10 generally designates a bridge lamp comprising a base 11, a post 12, an arm or bracket 13 from which a socket 14 is suspended, and a shade 15 surrounding the socket and its bulb. In order to hold the shade in proper position, a flat ring 16 is provided which is formed with a circular

depending flange 17 at right angles to the ring and surrounding the central aperture 18. The inner surface of the flange is formed with screw threads 19 adapted to be threadedly and rigidly secured to the lamp socket as will be readily understood by those versed in the art. The ring is formed with a plurality of flat lugs or extensions 20 which extend outwardly in the same plane as the ring proper and are formed integral therewith. In the present instance four lugs are provided, but a larger or lesser number may be employed if so desired.

The shade 15 includes an upper shade-supporting wire ring 21 and a lower wire ring 22 which are connected by brace wires 23. From the upper ring a plurality of wires 24 extend toward the center and their inner ends are brazed to the lower sides of the corresponding lugs 20 of the holder ring, said wires, lugs, wire ring 21 and holder ring being formed to lie in approximately the same plane in order to permit of easier manufacture and assemblage of the parts than in the usual construction.

Thus it will be seen that the holder ring 16 is of simple and practical construction, and the ends of wires 24 are quickly secured to the ring by brazing.

In Figure 5 the known manner of securing the shade to the holder ring is illustrated. Here the ring 25 comprises a threaded sleeve 26' constituting a circular flange at the central aperture of the ring body 26. The latter is bent downwardly and provided with a plurality of apertures 27 through which the wires 24 are introduced and curled around the free edge of the ring body.

It is obvious that the known ring holder is of more expensive construction, and more costly in assembling the shade than the new holder ring, which is marked by simplicity, strength of material and ease in assembling the shade.

While the invention is illustrated in connection with a bridge lamp, its application is nevertheless not limited thereto, but may be extended to all cases wherever a shade is to be supported.

The details of construction are also shown merely by way of example and not by way of limitation.

I, therefore, do not limit myself to any details, but want to include all changes, alterations and variations which constitute de-

partures within the scope of the invention as defined in the appended claim."

I claim:

The combination with a shade supporting 5 wire ring of a flat metal ring provided with a plurality of integral flat extensions at its circumference and in the same plane, a plurality of wires secured to said wire ring and brazed to the underside of said extensions,

said wire ring, wires and flat ring being 10 formed to be substantially in the same plane, and a depending circular and threaded flange at the central aperture of said flat ring and normal thereto and adapted to screw over a lamp socket. 15

In witness whereof I affix my signature.

LAWRENCE H. LEVINSON.
